UNITED STATES PATENT OFFICE.

ALVIN CARROLL GODDARD, OF NEW YORK, N. Y., ASSIGNOR TO J. F. BLANCHARD CO., OF NEW YORK, N. Y.

TRIM-FASTENING.

No. 908,858.

Specification of Letters Patent.

Patented Jan. 8, 1909.

Application filed June 4, 1908. Serial No. 436,597.

To all whom it may concern:

Be it known that I, ALVIN CARROLL GODDARD, a citizen of the United States, and a resident of the city of New York, Long Island City, borough of Queens, in the county of Queens and State of New York, have invented a new and Improved Trim - Fastening, of which the following is a full, clear, and exact description.

10 The invention relates to metal doors, windows, base-boards and like structures, and its object is to provide a new and improved trim or molding fastening, more especially designed for securely and quickly fastening trimmings or moldings in place without the use of screws, rivets or similar fastening devices, and without showing exterior projections, holes, marks or the like.

20 The invention consists of novel features and parts and combinations of the same, which will be more fully described herein-after and then pointed out in the claims.

25 A practical embodiment of the invention is represented in the accompanying drawings forming a part of this specification, in which similar characters of reference indicate corresponding parts in all the views.

30 Figure 1 is a sectional plan view of the improvement as applied to a door and door casing; Fig. 2 is a cross section of the door on the line 2—2 of Fig. 1, the moldings being removed; Fig. 3 is a perspective view of part of the receiving member; and Fig. 4 is a sectional plan view of a modified form of the improvement.

35 As illustrated in Fig. 1, the stile or cross bar A of the door is interlocked at its inner face A' with the panel B in the usual manner, and on the said face A' on opposite sides 40 of the panel B are struck-up lugs A² adapted to receive flanges C' formed on the molding C adapted to rest on the faces of the panel B and on the face of the side A', it being understood that the flanges C' are driven in between the face of the side A' and the inner 45 faces of the struck-up lugs A², and the contacting portions of the flanges C' and the lugs A² are provided with interlocking teeth, to securely hold the molding or trimming C in position. By the arrangement described the molding or trimming C is locked in place without the use of screws, rivets or similar fastening devices, and it is only necessary for

the operator to drive the toothed flanges C' in position between the face of the side A' and the lugs A², as above explained.

55 The jamb D of the door opening E is provided at each end with a pocket D' having its outer member formed with teeth D² at the inside, and into each pocket is driven the toothed flange F' of the trim F, so as to securely interlock the flange F' and the pocket D' with each other, as will be readily seen by reference to Figs. 1 and 3. The other end of the trim F is formed with a pocket F² having 60 a toothed member, and into the pocket extends the toothed flange G' of a bracket G attached to the wall E', as indicated in Fig. 1.

65 Instead of providing the interlocking members with teeth, as shown in Figs. 1 and 3 and described above, the interlocking members may be corrugated, for instance as shown in Fig. 4, the receiving member or support H is formed with a pocket H' into which is driven the flange I' of the molding 70 I, the flange I' having a corrugated portion I² and the outer member of the pocket H' having a corrugated portion H² meshing 75 with one of the corrugations I² whenever the corrugated portion of the flange I' is driven 80 into the pocket.

75 The trim or molding fastening shown and described can be very cheaply manufactured, and the moldings or trimmings can be securely attached to their supports, without 85 the use of special fastening devices which are liable to mar the appearance of the door, window or like structure on which the molding is applied.

80 Having thus described my invention, I claim as new and desire to secure by Letters Patent:

1. A trim fastening comprising a trim, and a support one having a flange provided with a series of interlocking projections, and the other having spaced members between which passes the flange, one of said spaced members having interlocking means for engagement with the interlocking projections of the flange.

100 2. A trim fastening, comprising a trim having a flange provided with a series of interlocking projections, and a support for the trim having spaced members between which passes the flange, one of said spaced members having interlocking means, for engage-

ment with the projections of the flange, when the latter is forced between the said members.

3. A trim fastening, comprising a trim having a toothed flange, and a support for the trim having struck-up lugs toothed on the inner face, the said flange being adapted to pass between the said support and its struck-up lugs, the teeth of the flange and 10 the teeth of the lugs interlocking with each other.

4. A door, comprising cross bars and sides, each having struck-up toothed lugs on their inner faces, panels interlocked with the inner 15 faces of the cross bars and sides, and moldings having toothed flanges driven between the said inner faces and the struck-up lugs, the teeth of the flanges and lugs interlocking with each other.

20 5. In combination with a door, window, base board and like structure, a trim, the said structure and the said trim having members provided on their contacting surfaces with interlocking teeth.

6. A trim fastening, comprising a trim, and a support, one having a flange and the other spaced members between which passes the flange, the flange and one of said mem- 25

bers being provided on their contacting portions with interlocking teeth. 30

7. A trim fastening, comprising a trim having a flange, and a support for the trim having spaced members between which the flange is adapted to be driven, the said flange and the inner face of the outer one of said 35 spaced members being provided with integral interlocking means adapted to engage each other when the flange is forced between the said members.

8. A trim fastening comprising a trim, and 40 a support, one having a flange and the other spaced members between which passes the flange, the said flange and one of the spaced members having interlocking means adapted to engage each other when the parts are 45 forced together, the interlocking means being arranged to hold the flange and the spaced members in adjustable relation to each other.

In testimony whereof I have signed my 50 name to this specification in the presence of two subscribing witnesses.

ALVIN CARRROLL GODDARD.
